APPARATUS FOR COOKING THICK MASSES.

1,366,431.

Specification of Letters Patent. Patented Jan. 25, 1921.

Application filed December 20, 1917. Serial No. 208,062.

To all whom it may concern:

Be it known that we, EDGAR A. STROHMAIER and BENTON A. HOOK, citizens of the United States, and residents, respectively, of San Mateo, county of San Mateo, and Centerville, county of Alameda, both in the State of California, have invented a certain new and useful Apparatus for Cooking Thick Masses, of which the following is a specification.

The invention relates to a process of and an apparatus for cooking thick masses or pulps, such as the tomato pulp from which catsup is made.

Objects of the invention are to provide a process of cooking thick pulps and to provide an apparatus to accomplish the cooking.

In the manufacture of tomato catsup, the raw tomato pulp is charged into a kettle having steam coils arranged therein at the bottom and steam is fed through the coils to heat and boil the tomato pulp for a sufficient length of time to cook it. The raw tomato pulp is very thick and sluggish, so that when the steam is turned on through the coils, that portion of the pulp lying against the coils becomes overheated and sticks to the coils and becomes blackened and burned, impairing the transfer of heat from the coils and the quality of the pulp, and also causing a waste of pulp. After every batch of pulp is cooked it is necessary to scrape or scrub the caked material from the coils, before another batch can be charged into the kettle.

It is an object of our invention to provide a process of cooking thick pulp which eliminates this caking and burning of the material on the steam coils and to provide an apparatus for carrying out the process.

The invention possesses other advantageous features, some of which, with the foregoing, will be set forth at length in the following description where we shall outline in full the process of our invention when applied to tomato pulp and that form of apparatus which we have selected for illustration in the drawings accompanying and forming part of the present specification.

Referring to said drawings:

Figure 1 is a vertical section of the cooking kettle.

Fig. 2 is a plan view of the kettle.

Fig. 3 is a vertical section of the ejector.

In accordance with our invention we

charge the cold raw pulp into a kettle and agitate it with a jet of steam or compressed air. The jet of steam or compressed air produces a circulation of the pulp, so that when the steam is turned into the coils, the pulp is circulated past the coils, preventing the overheating of the pulp at the coils and the consequent burning of the pulp. After the pulp has been heated by the coils to the boiling point, the agitation and circulation produced by the boiling is sufficient to prevent overheating of the pulp at the coils and the jet of agitating fluid may be turned off. While we may employ either steam or compressed air as the agitating fluid, we prefer to use steam since the steam so employed assists in bringing the mass of pulp to the boiling temperature. Also, as the thick pulp is heated it becomes thinner and more fluid so that it is more readily agitated. The steam may be turned into the steam coils as soon as the jet has started the circulation of the pulp, or when steam is used as the agitating medium, the steam may not be introduced into the coils until the mass has approached the boiling temperature. Whether the steam is turned into the coils before or after the pulp becomes heated, it is desirable to maintain the agitating jet in action until the mass begins to boil, after which the jet may be turned off.

In practice, the steam jet is turned on when the kettle is only partly full and the charging of the kettle is continued until it contains the desired charge. By this time the mass is well heated and the steam is turned into the steam coils and as soon as the mass is brought to a boil, the steam jet is turned off. When compressed air is used as the agitating fluid, the steam may be turned into the steam coils as soon as the mass is in thorough agitation.

Arranged within the kettle 2, and preferably adjacent the bottom are the copper steam coils which preferably consist of two coils, the outer coil 3 and the inner coil 4, the coils being spaced apart radially to permit circulation of the pulp between them. Steam is admitted to the coils from the steam pipe 5 through the nipples 6—7 and discharged through the nipples 8—9.

Depending into the kettle at the side thereof and connected to the steam pipe 5, is a pipe 12 on the lower end of which is secured an ejector 13. The ejector is prefer-

ably disposed between the inner and outer coils 3—4 and is preferably arranged adjacent the bottom of the kettle, so that it may be brought into operation when only a small portion of the complete charge has been entered. The ejector comprises a spider 14 secured to the end of the pipe 12, a converging nozzle 15 secured to the spider and a steam nozzle 16 forming an extension of the steam pipe and extending down into the nozzle 15. The pulp is drawn into the upper end of the nozzle 15 by the steam jet and is forcibly discharged at considerable velocity from the lower end of the nozzle and is simultaneously heated by the steam. The velocity of discharge agitates and causes a circulation of the pulp so that it becomes uniformly heated. The pipes 5 and 12 are provided with valves 17—18 for controlling the flow of steam. By the use of this process or apparatus the pulp does not adhere to the steam coils and they remain bright and clean, overcoming a loss of pulp and time and producing a purer food product.

25 We claim:

1. A cooking apparatus comprising a kettle, a steam coil arranged within the kettle adjacent the bottom, a pipe depending into the vessel at one side thereof and terminating adjacent said steam coil and an ejector nozzle open at both ends, mounted on the lower end of the pipe.

2. An apparatus for cooking thick masses, comprising a kettle having a rounded bottom, heating means, arranged within the

kettle adjacent the bottom, a pipe depending into the vessel, an ejector arranged on the lower end of the pipe to discharge a jet close to said bottom, and means for supplying steam whereby a circulation of the mass about said heating means is caused.

3. A cooking apparatus comprising a kettle, a steam coil arranged within the kettle adjacent the bottom, a pipe depending into the vessel and terminating in a nozzle adjacent the bottom of the kettle, a spider arranged on said pipe, and a sleeve disposed on said spider and having a wall spaced from and surrounding said pipe nozzle and converging ahead of the pipe nozzle to form a restricted discharge aperture.

4. An apparatus for cooking thick masses, comprising a kettle having a rounded bottom, heating means arranged within the kettle adjacent the bottom, a pipe depending into the vessel, an ejector arranged on the lower end of the pipe, to discharge a jet vertically downward close to the curved bottom, and means for supplying steam whereby a circulation of the mass about said heating means is caused.

In testimony whereof we have hereunto set our respective hands at Centerville, California, this 13th day of December, 1917.
